UNITED STATES PATENT OFFICE.

MICHAEL LIPTAK, OF ST. PAUL, MINNESOTA, ASSIGNOR TO A. P. GREEN FIRE BRICK COMPANY, OF MEXICO, MISSOURI, A CORPORATION OF MISSOURI.

FURNACE WALL.

Application filed July 17, 1922. Serial No. 575,737.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art 10 to which it appertains to make and use the same.

My present invention relates to furnace wall structures and, in a general way, is in the nature of an improvement on or refinement 15 of the wall structure disclosed and broadly claimed in my pending application Serial Number 550,841, filed April 8, 1922.

Generally stated, the invention consists of the novel construction, combinations and arrangements 20 of parts hereinafter described and defined in the claims. The various features of novelty will appear in the description of the accompanying drawings, which illustrate a preferred form or embodiment 25 of the several features of this invention.

In said drawings, wherein like characters indicate like parts throughout the several views,

Fig. 1 is an elevation showing a portion 30 of the wall embodying my invention, looking at said wall from the exterior thereof;

Fig. 2 is a perspective with some parts removed and some parts sectioned, illustrating the wall shown in Fig. 1, looking at the 35 inner face thereof;

Fig. 3 is a horizontal section taken approximately on the line 3—3 of Fig. 2;

Fig. 4 is a vertical section taken approximately on the line 4—4 of Fig. 3;

Fig. 5 is a perspective showing the upper and lower sections of one of the shelf-anchoring boxes, looking at the inner side thereof, the vertical sections being separated;

Fig. 6 is a perspective showing the upper box section illustrated in Fig. 5, turned upside down to illustrate the internal structure thereof;

Fig. 7 is a perspective showing the lower box section illustrated in Fig. 5, turned upside down to better illustrate the external structure thereof; and

Fig. 8 is a fragmentary vertical section illustrating a slightly modified arrangement 55 of the wall-forming elements.

The complete wall structure illustrated is made up of what may be designated as a "permanent masonry outer wall" and a "replaceable high refractory inner wall." The permanent outer wall has belts or rows of tile or baked fire clay, self-anchoring boxes, and the replaceable inner wall includes shelf-forming blocks or fire tiles that project into and are anchored within the cooperating anchor boxes. In this arrangement, 60 the lower portions of the anchor boxes afford sills, the upper portions of said boxes afford lintels, and the end walls of said boxes afford pilasters, and, moreover, said arrangement of the boxes affords horizontally spaced pockets and vertically spaced horizontal rows. 70

As a highly important additional feature of novelty, giving greatly improved facility in the original erection and in making repairs, these tile or masonry anchor boxes are horizontally split or divided. 75

In most instances, the tile or masonry anchor boxes are placed end to end in horizontal rows, forming belts, and said belts 80 are vertically spaced with brickwork between the same, as illustrated in the main views of the drawings, but the said boxes may be placed one on top of the other and thus made to form the entire outer or permanent wall, 85 as illustrated in Fig. 8.

Describing first the construction illustrated in Figs. 1 to 7, inclusive, the numerals 9 and 10 indicate, respectively, the lower and upper sections of the tile or masonry anchor boxes. The said sections, when put together, 90 form a rectangular box with a rectangular opening at the inner face of the permanent outer wall. The numeral 11 indicates brickwork; preferably commercial bricks, built in horizontal belts between the horizontal belts or rows of anchor boxes. 95

The replaceable inner wall should be made up entirely of high refractory bricks or tiles and, as shown, it comprises replaceable horizontal belts of fire bricks 12 and, between said belts, horizontal rows or layers of shelf-forming blocks or long fire bricks 13 placed in groups and extended from the replaceable wall into the cooperating anchor boxes. 100 As preferably designed, these shelf-forming blocks 13 have the vertical cross-section of commercial fire bricks, but, of course, such dimensions may be varied. The sill-forming lower portions of the lower box sections 9 110

are formed with raised lock ledges 14, and the inner ends of the shelf-forming blocks 13 are formed with depressed lock ledges 15 that are adapted to overlap and interlock with said ledges 14 when the blocks 13 are seated, as best shown in Figs. 2 and 4. To hold said blocks 13 interlocked to the sill-forming portions of the anchor boxes, wedge-acting key blocks or bricks 16 are used. These key blocks 16 are preferably slightly tapered and the under surfaces of the lintel-forming portions of the upper block sections 10 are preferably correspondingly beveled. The shelf-forming blocks 13, 15 preferably but not necessarily, extend completely through the replaceable inner wall, while the key blocks 16 preferably do not extend completely through said wall, and the spaces beyond the inner ends of said blocks 16 are filled in with fire bricks 17. Also, the horizontal spaces between the groups of shelf-forming blocks 13 are filled in with fire bricks 18.

It is highly important to note that when the shelf-forming blocks 13 and key blocks 16 are secured in working position, they, together, but chiefly the former, form horizontal shelves that support the intervening horizontal belts of replaceable brickwork 12. Of course, said blocks 13 and 16 are also replaceable.

Under intense heat, the fire bricks 12 will tend to fuse to the masonry elements of the permanent outer wall and, moreover, when the inner wall is badly burned away, there is a tendency for the shelf-forming blocks 13 to fuse to the anchor boxes. To prevent fusion or welding of the fire bricks 12 to the anchor boxes and brickwork of the permanent outer wall, said walls are laid with a slight vertical air space at 19.

For an important purpose, clearance spaces 20 are left between the back walls of the anchor boxes and adjacent ends of the blocks 13, as best shown in Figs. 3 and 4, and these clearance spaces 20 are extended at 20^a to afford clearance between the end walls of said boxes and the adjacent sides of the outer blocks 13 of the groups, (see particularly Fig. 3). With this arrangement, even if the lower portions of the shelf-forming blocks 13 should fuse to the sill-forming portions of the anchor boxes, said blocks may be loosened by pounding on the exposed ends of said blocks and thereby driving the same back into the pockets of the anchor boxes. The side clearance spaces 20^a permit the blocks 13 to be forced apart laterally and thus separated, even if more or less fused together. Said blocks 13 may be thus driven back into the pockets, either before or after the key blocks 16 have been loosened up or removed, but said key blocks must be removed before the shelf-forming blocks 13 can be removed from the pockets

in the anchor boxes. To facilitate the removal of said key blocks, the outer walls of the upper box sections 10, in line with at least some of said key blocks, are formed with holes 21. In the arrangement illustrated, the blocks 13 are arranged in groups of three so positioned that two key blocks may be driven out of position by a metal punch or rod inserted through the particular hole. Normally, the holes 21 may be closed by plugs 22 of fire clay or the like, which, of course, may be readily driven out of position, (see particularly Figs. 1 and 4).

The composite wall described may be used in association with or independently of buckstays, and if buckstays are employed, it may be used either in connection with vertical or horizontal buckstays or both. In the drawings, I have illustrated this wall as anchored to vertical buckstays, which, in turn, are connected by horizontal buckstays. The vertical buckstays are shown as of the usual construction, being made up of pairs of metallic channel beams 23 placed back to back but slightly spaced apart, and the horizontal buckstays are shown as made up of similar channel beams 24 placed back to back but slightly spaced and rigidly connected at their ends by rivets or otherwise to the vertical buckstays, (see particularly Figs. 1 and 4).

For anchoring the anchor boxes, in some instances, to the vertical buckstays and, in other instances, to the horizontal buckstays, I provide anchor bolts 25 equipped with nuts 26 at their threaded outer ends and at their inner ends having horizontally bent or projecting grapple lugs 27. For cooperation with these anchor bolts, the lower box sections 9, in their bottoms, are formed with grooves 28 that extend to the outer faces of said sections and, at their inner extremities, terminate in notches 29 that afford seats for the grapple lugs 27 of the anchor bolts. Said anchor bolts may be inserted into or moved from interlocking engagement with the said block sections when their lugs 27 are turned into horizontal positions, and they will be interlocked therewith when said lugs are turned vertically. The outer portions of the anchor bolts are, of course, passed between the members of the buckstays and when their nuts 26 are tightened, the anchor block sections 9 will be directly anchored to said buckstays and, of course, the entire wall will be indirectly anchored to such buckstays.

In Fig. 4, the numeral 30 indicates a rod or punch inserted through one of the perforations 21 in position to drive out the wedge blocks 16.

By reference to Fig. 1, it will be noted that the anchor boxes of the different vertical belts are set so that their vertical

joints are broken or staggered. This not only gives the best kind of a bond in the wall but forms the so-called permanent outer wall in such manner that if, at any time, it should be necessary to replace one or more of the anchor boxes or certain of the bricks 11, such operations may be performed without tearing down said wall or without removing therefrom any considerable portion thereof except the parts to be actually replaced. The outer extremities of the grooves 28, in the lower box sections 9, may be normally closed by plugs 31 of fire clay or other suitable material which may be readily displaced.

The construction illustrated in Fig. 8 is like that above described except that the permanent outer wall is built up entirely of the anchor boxes 9—10, which arrangement materially reduces the number of bricks and the vertical extensions of the fire brick belts 12. For instance, in the structure illustrated in the main views, the brick belts 12 are made up of nine horizontal courses of bricks, while in Fig. 2, fire brick belts 12^a are made up of five horizontal courses of said bricks, but, of course, in either arrangement, the number of bricks may be varied.

30 The wall structure described makes the replacement of any part or zone of the replaceable inner wall a very easy matter, which may be quickly performed by a workman ordinarily skilled in the art.

35 What I claim is:

1. A wall structure made up of a masonry outer wall and a replaceable inner wall, said outer wall including refractory tile anchoring boxes and said inner wall including shelf-forming blocks extended into and anchored within said anchor boxes.

2. A wall structure made up of a masonry outer wall and a replaceable inner wall, said outer wall including refractory tile anchoring boxes and said inner wall including shelf-forming blocks extended into and anchored within said anchor boxes, said shelf-forming blocks and boxes having positive interlocking engagement.

50 3. A wall structure made up of a masonry outer wall and a replaceable inner wall, said outer wall including refractory tile anchoring boxes and said inner wall including shelf-forming blocks extended into and anchored within said anchor boxes, said anchor boxes being rectangular, the bottom portions thereof affording sills, the top portions thereof affording lintels and the end portions thereof affording pilasters in said outer wall.

45 4. A wall structure made up of a masonry outer wall and a replaceable inner wall, said outer wall including refractory tile anchoring boxes and said inner wall including shelf-forming blocks extended into and

anchored within said anchor boxes, and key blocks inserted between said shelf-forming blocks and the tops of the cooperating anchor boxes.

5. A wall structure made up of a masonry outer wall and a replaceable inner wall, said outer wall including refractory tile anchoring boxes and said inner wall including shelf-forming blocks extended into and anchored within said anchor boxes, said shelf-forming blocks and boxes having positive interlocking engagement, and key blocks inserted between said shelf-forming blocks and the tops of the cooperating anchor boxes.

6. A wall structure made up of a masonry outer wall and a replaceable inner wall, said outer wall including refractory tile anchoring boxes and said inner wall including shelf-forming blocks extended into and anchored within said anchor boxes, said anchor boxes being rectangular, the bottom portions thereof affording sills, the top portions thereof affording lintels and the end portions thereof affording pilasters in said outer wall, and key blocks inserted between said shelf-forming blocks and the tops of the cooperating anchor boxes.

7. The structure defined in claim 1 in which said anchor boxes are formed with pockets, the walls of which are spaced from the inserted inner ends of said shelf-forming blocks so as to permit said blocks to be driven slightly from normal position farther into said pockets.

8. The structure defined in claim 1 in which said anchor boxes are formed with pockets, the walls of which are spaced from the inserted inner ends of said shelf-forming blocks so as to permit said blocks to be driven slightly from normal position farther into said pockets, said pockets being further formed with spaces between the same and the sides of the adjacent groups of cooperating shelf-forming blocks.

9. The structure defined in claim 4 in which said anchor boxes are provided in their outer walls with perforations through which a punch may be inserted to drive said key blocks from position.

10. The structure defined in claim 5 in which said anchor boxes are provided in their outer walls with perforations through which a punch may be inserted to drive said key blocks from position.

11. The structure defined in claim 5 in which said anchor boxes are provided in their outer walls with perforations through which a punch may be inserted to drive said key blocks from position, and which anchor boxes are formed with pockets, the walls of which are spaced from the inserted ends of said shelf-forming blocks so as to permit said blocks to be driven slightly from normal positions further into said pockets.

- 4
12. The structure defined in claim 11 in which the pockets of said anchor boxes are further formed with spaces between the same and the sides of the adjacent cooperating shelf-forming blocks.
13. A wall structure made up of a permanent outer wall and a replaceable inner wall, said outer wall including divided or two-part anchoring boxes and said inner wall including shelf-forming blocks extended into and anchored within said boxes.
14. A wall structure made up of a masonry outer wall and a replaceable inner wall, said outer wall including non-metallic tile anchoring boxes and said inner wall including shelf-forming blocks extended into and anchored within said anchor boxes, the said anchoring boxes being split or divided but assembled to form complete boxes.
15. A wall structure made up of a masonry outer wall and a replaceable inner wall, said outer wall including refractory tile anchoring boxes and said inner wall including shelf-forming blocks extended into and anchored within said anchor boxes, said shelf-forming blocks and boxes having positive interlocking engagement, the said anchoring boxes being made up of sections assembled to form complete boxes.
16. A wall structure made up of a masonry outer wall and a replaceable inner wall, said outer wall including refractory tile anchoring boxes and said inner wall including shelf-forming blocks extended into and anchored within said anchor boxes,
- said anchor boxes being horizontally split or divided.
17. The structure defined in claim 5 in which said anchoring boxes are horizontally split or divided.
18. The structure defined in claim 5 in which said anchoring boxes are horizontally split or divided and the upper sections of which, in their outer walls, are formed with perforations through which a punch may be inserted to drive said key blocks from working position.
19. As a new article of manufacture, a tile anchor box of rectangular formation provided with rectangular pocket-forming cavities that extend less than from end to end thereof.
20. As a new article of manufacture, a tile anchor box of rectangular formation provided with rectangular pocket-forming cavities, and having a punch hole in its vertical web.
21. As a new article of manufacture, a tile anchor box of rectangular formation provided with rectangular pocket-forming cavities, the bottom of said pocket having a raised lock ledge adapted for interlocking engagement with a shelf-forming block.
22. The structure defined in claim 19 in which said box is horizontally divided.
23. The structure defined in claim 19 in which said box is horizontally divided, the lower section of said box having a raised lock ledge in its pocket-forming cavity.
- In testimony whereof I affix my signature.
- MICHAEL LIPTAK.
